United States Patent Office.

HENRY BERGER, OF NEW YORK, N. Y.

Design No. 3,614, dated August 17, 1869.

DESIGN FOR A CENTRE-PIECE.

The Schedule referred to in these Letters Patent and making part of the same.

To all whom it may concern:

Be it known that I, HENRY BERGER, of the city, county, and State of New York, have invented a new and original Design for a Centre-Piece; and I do hereby declare the following to be a full, clear, and exact description thereof, which will enable those skilled in the art to make and use the same, reference being had to the accompanying drawing, forming part of this specification.

The drawing, consisting of one figure, shows my new design for centre-piece.

What I claim as new, and desire to secure by Letters Patent, is—

The design for centre-piece, above described and shown.

This specification signed by me, this 23d day of July, 1869.

HENRY BERGER.
